(57) **CLAIM**

The ornamental design for a dryer for clothing as shown and described.

DESCRIPTION

1. Dryer for clothing

1.1 : Perspective view

1.2 : Front view

1.3 : Back view

1.4 : Left view

1.5 : Right view

1.6 : Top view

1.7 : Bottom view

1.8 : Front view 2

The broken lines depict portions of the dryer for clothing that form no part of the claimed design; this design has a storage box in the bottom; reproduction 1.8 is a front view showing the state that the display of the claimed design has been operated.

1 Claim, 8 Drawing Sheets
